UNITED STATES PATENT OFFICE.

VICTOR SJÖSTRÖM, OF LOS ANGELES, CALIFORNIA.

GAS HEATING APPLIANCE.

1,376,650.

Specification of Letters Patent.

Patented May 3, 1921.

Application filed November 19, 1918. Serial No. 264,105.

To all whom it may concern:

Be it known that I, VICTOR SJÖSTRÖM, a subject of the King of Sweden, and a resident of Los Angeles, in the county of Los Angeles and State of California, have invented new and useful Improvements in Gas Heating Appliances, of which the following is a specification.

This invention relates to heating appliances and has particular relation to heating stoves, in which gas is used as a fuel. The heater is adapted for use in the form of a stove, and an object of my invention is to provide a heater having the walls surrounding the combustion chamber and the radiating portions formed of an integral metal casting, thus providing against the burning out of the walls of the heater, and suitable channels, or passages being provided in the heater for directing a draft therethrough and for venting the heater to the atmosphere.

With the above and other objects in view, my invention comprises certain novel construction features, combinations and arrangements of parts which will be herein-after more completely described and claimed.

Two practical embodiments of my invention are illustrated in the accompanying drawings, forming a part of this application, in which:

Figure 1 is an elevation of my invention when arranged as an ordinary stove or heater, one of the peripheral grilles being omitted from the exterior thereof for disclosing the exterior form of the device.

Fig. 2 is a composite plan of the form of heater shown in Fig. 1, a portion thereof being in section on the line 2-2 of Fig. 3.

Fig. 3 is a sectional elevation of the same on the line 3-3 of Fig. 2.

Fig. 4 is a sectional plan of the same on the line 4-4 of Fig. 3.

Referring now particularly to the above mentioned and described drawings, I will describe the heater shown in Figs. 1 to 4 inclusive, *i. e.*, a portable stove or heater.

The upper and lower portions of the body in this form of heater, as shown, is circular in cross section and composed of a single integral cast metal cylinder B having legs 1 attached to the bottom or separate base 2 thereof, said base having a ring 3 with arms 4 leading therefrom to the center, thus providing air spaces between the arms. At the

center of the base 2 a depending boss 5 is integrally formed therewith and is provided with a vertical bore 6, closed at the lower end and open at the upper end above the 60 surface of the base 2, a gas pipe 7 being connected with the bore 6. Said pipe may be conveniently supported at its outer end in a depending lug 8 formed on the apron of the base and bored so as to permit the 65 extension of the pipe therethrough, as shown. The outer end of pipe 7 has a valve casing 9 thereon which is adapted to be connected with a flexible tube leading to a source of gas supply. 70

The body member B has a centrally formed combustion chamber 10 which is surrounded by an annular wall 11 extending from the upper surface of the base 2 to a point substantially below the enlarged 75 dome 19. Exterior of the wall 11 I provide a plurality of vertical draft passages 13, within wall 14, which communicate at the bottom with an annular chamber 15 formed between the wall 11 and the 80 lower portion of outer wall 14 at the bottom of the member B, the floor 17 of which is adapted to rest upon and be attached to the ring of the base 2 by means of screws 18. The upper chamber 12 is in 85 closed by means of a dome 19 which is integrally connected with the outer wall 14. Thus, the chamber 10 communicates directly with the upper chamber 12, and chambers 12 and 15 are in communication by 90 means of the passages 13. The chamber 15 is vented to the outside by means of a vent pipe 20.

The dome 19 is provided with an opening 21 in the center which is covered by a cap 95 22 and slightly to one side of the center a mica disk 23 is held in place over an opening 24 by means of a retainer 25 so that the operation of the burner may be visible to the eye. The exterior of the body B in 100 the wall 14 has peripheral recesses 26 formed therein which are covered by ornamental grilles 27, suitably held in place and flush with the outer wall 14 and in the wall 11 of one of the recesses 26 a suitable opening 105 28 is provided through which a match may be inserted into the combustion chamber for lighting the heater. Vent pipe 20 has a suitable damper 29 therein exterior of the heater so that the draft may be regulated thereby. 110

The burner is composed of a plurality of sections 30, each having a plurality of arms,

as shown, with small jet apertures 31 therein at the tops, and a bell shaped mixing receptacle 32. The burner sections and the mixing receptacle have projections 33 which are 5 adapted to be screwed into corresponding openings in adjacent members, so as to be leak proof, the mixer 32 being inverted and attached to the base 2, as shown. The upper section of burner is provided with a suitable 10 closure 34 for closing the passage 35 formed in the burners so that the gas admitted from the passage 6 in boss 5 of the base will be projected through bore, or passage, 35 and therefrom into the chambers 36 of the burner 15 sections, from which the gas is discharged upwardly through the jets 31 into the combustion chamber of the heater.

The heat rises in the combustion chamber to the upper chamber 12 and is directed 20 around the curved top thereof into the vertical passages 13 and from thence all noxious fumes and the products of combustion are discharged through the annular chamber 15 at the bottom into the vent 20 and thence 25 to the outside, none of the fumes being admitted to the room. The great amount of radiating surface provided in the inner and outer walls and the grilles 27 insures a maximum degree of heat from a relatively small 30 heater and also eliminates the usual unpleasant results obtained from gas heaters.

What I claim is:

1. A gas heater comprising an integrally cast body having inner and outer walls and 35 a continuous annular passage therebetween at the bottom, a dome having a heat chamber therein, the upper end of said inner wall being spaced from said dome, a combustion chamber being formed interiorly of said inner wall, in communication with said heat 40

chamber, the peripheral portion of said body being subdivided into a plurality of radiating chambers open to the atmosphere extending from said dome to the top of said annular passage, and a plurality of alternating heat passages affording communication between said heat chamber and said annular passage, a vent pipe connected with said annular passage for discharging the products of combustion and a plurality of grilles 50 covering said radiating chambers and attached to said outer wall. 45

2. A gas heater having an integrally cast body having inner and outer walls and a continuous annular passage therebetween at 55 the bottom, and a dome having a heat chamber therein, the upper end of said inner wall being spaced from said dome, a combustion chamber being formed interiorly of said inner wall in communication with said heat 60 chamber, the peripheral portion of said body being subdivided into a plurality of radiating chambers open to the atmosphere and extending from said dome to the top of said annular passage, and a plurality of alternating 65 heat passages affording communication between said heat chamber and said annular passage, a vent pipe connected with said annular passage for discharging the products of combustion, a plurality of grilles covering said radiating chambers and attached to said outer wall, a burner in said combustion chamber and an opening in the wall of 70 said body, whereby the gas from said burner may be ignited from the exterior of the 75 heater.

VICTOR SJÖSTRÖM.
